MATTHEW F. CONNETT AND MATTHEW F. CONNETT, JR., OF LITTLE ROCK,
ARKANSAS.

BALING-PRESS.

SPECIFICATION forming part of Letters Patent No. 236,988, dated January 25, 1881.

Application filed July 3, 1880. (No model.)

To all whom it may concern:

Be it known that we, MATTHEW F. CONNETT and MATTHEW F. CONNETT, Jr., of Little Rock, in the county of Pulaski and State of Arkansas, have invented a new and valuable Improvement in Baling-Presses; and we do hereby declare that the following is a full, clear, and exact description of the construction and operation of the same, reference being had to the annexed drawings, making a part of this specification, and to the letters and figures of reference marked thereon.

Figure 1 of the drawings is a representation of a vertical section of our improved press, and Fig. 2 is a horizontal section of the same.

This invention has relation to improvements in bailing and compressing machines; and it consists in the arrangement and novel construction of the various parts of the press, and in the combination of the devices used, as will be hereinafter more fully shown and described.

In the annexed drawings, the letter A designates the rectangular base of the press, having at its corners four strong upright metallic posts, B, which support fixedly at their upper ends the stationary bed C. The uprights are suitably secured both to the bed and base, and are strongly braced together at proper intervals. The bed is also connected to the upper braces by bolts and inclined truss-plates. We do not confine ourselves, however, to any special construction of the press-frame, any form thereof having the requisite strength being suited to our purposes.

D indicates the follower, of suitable construction, arranged between the uprights B, and vertically movable to or from the bed for the purpose of admitting the material to be baled, and pressing the same, or of compressing a bale already formed.

G G and G' G' indicate strong metallic levers, composed each of the two metallic plates, through-bolted together in pairs. The levers G G extend through the interval between the plates G' G', and extend considerably beyond the same, forming the power-arms H, and the levers G' G' are extended beyond the levers G G, forming similar arms, H'. The levers G are pivoted to the under side of the follower by bolts a, extending through or their equivalent in the said follower, es in the

ends of the said levers, and the levers G' G' are pivoted to the base by means of similar bolts b. The levers G G' are pivoted together after the manner of toggles at their intersection by means of the bolts c c', and on the bolt c, in the interval between the plates d, are arranged the independent pulleys o o. The power-arms H of the levers G are provided, at their ends, with the pulleys e e', and the power-arms H' of the levers G' with similar pulleys f f'.

It is evident that the follower is run up when these toggle-jointed levers are straightened out. This is accomplished by a double-conical windlass, operated by a suitable motor through the medium of the ropes R R', which ropes are prevented from slipping on the windlass by forming grooves therein or by other equivalent means. The rope R is attached to the windlass by one end at the point of its greatest diameter, passes thence between the plates d of levers G, over and around the pulley e at the far side of the machine, thence back to the corresponding pulley e at the near side thereof, around which it is passed. It is then carried back over the pulley e' at the far side of the machine, thence around pulley e' at the near side thereof, thence over and around the pulley o on the bolt c. It is thence carried up around the pulley f, nearest the motor, thence back over and around the pulley f at the far side of the machine, thence back to the pulley f', thence to the second pulley f', and thence to the windlass, to which it is then secured. The rope R' is secured to the other conical part of the windlass, and pursues an identical course over the pulleys of the remaining levers G G'. The rotation of the windlass at its inception runs the follower up rapidly, there being but little resistance to overcome; but as the resistance increases the power exercised by the windlass is correspondingly increased, owing to its constantly-decreasing diameter. The passing of the levers G between levers G' allows them to be straightened out completely, and the peculiar arrangement of the pulleys in the power ends of said levers and the method and course of the ropes R R' around the said pulleys, gives enormous compressing power.

In order to prevent the follower from tip-

ping while being run up, it is provided on its under side with strong T-shaped guides N, the horizontal branches of which are bolted to the under side of the follower, and their vertical branches engaged between parallel guideways w, secured to the frame.

We are aware that a follower of a press operated by toggle-jointed levers is not broadly new; hence we do not broadly claim such devices.

What we claim as new, and desire to secure by Letters Patent, is—

In a baling and compressing machine consisting of the posts B, having base A and bed C, the follower D, provided with guides N and

guideways, the levers G G', pivoted together at their intersections, and having power-arms H H', provided with pulleys e e' f f' o, the levers G, pivoted to the follower, the levers G', pivoted to the base, and the ropes R R', engaging said pulleys, all constructed and arranged to operate as shown and described.

In testimony that we claim the above we have hereunto subscribed our names in the presence of two witnesses.

MATTHEW F. CONNETT.
